[57] CLAIM

The ornamental design for a handgrip for a knife, as shown and described.

DESCRIPTION

FIG. 1 is a front elevational view of a handgrip for a knife showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a front elevational view thereof showing a holder cover in an alternate position; and,

FIG. 9 is a front elevational view thereof with a blade shown in broken lines.

The broken line portion of FIG. 9 is for illustrative purposes only and forms no part of the claimed design.
